D. DICK.
AIR AND GAS ENGINE.

No. 63,619.

Patented Apr. 9, 1867.

United States Patent Office.

DAVID DICK, OF MEADVILLE, PENNSYLVANIA.

Letters Patent No. 63,619, dated April 9, 1867.

IMPROVEMENT IN AIR AND GAS ENGINES.

The Schedule referred to in these Letters Patent and making part of the same.

TO ALL WHOM IT MAY CONCERN:

Be it known that I, DAVID DICK, of Meadville, Crawford county, Pennsylvania, have invented a new and useful Improvement in Atmospheric Engines; and I do hereby declare that the following is a full, clear, and exact description of the construction and operation of the same, reference being had to the annexed drawings, making a part of this specification, in which—

Figure 1 is a view in elevation of one form of my improvement.

Figure 2 is a vertical central longitudinal section through the generator and closed chamber.

Figure 3 is a transverse section through the same.

Figure 4 is a top view, showing a slide valve and its openings with portions of the openings into the generator.

Figure 5 is a transverse section through the generator to show the slide fastening for the valve; and

Figure 6 is a longitudinal central section of a generator exhibiting a modification of the mode of ventilating.

Like letters refer to like parts in all the figures of the drawings.

It is the object of my invention to produce motive power by expanding the air in a generator communicating with the working cylinder of the engine and heating the air with some combustible material contained in and alternately ignited and extinguished in a closed chamber connected with or made a part of the generator, and to control the ignition of the combustible material with absolute precision by the motion of the engine; and to this end my invention consists, first, in heating the air for an air engine within a generator by combustion produced from some material contained in a closed chamber connected with or made a part of the generator; second, in alternately-creating and extinguishing combustion in the generator by introducing therein a combustible material to be ignited as it is introduced, and thus expand the air to exert the force required; third, in simultaneously expelling the air which has been deprived of its oxygen from and introducing fresh air into the generator by a revolving plate that shall vibrate back and forth alternately around the internal diameter of the cylinder against a longitudinal diaphragm; fourth, in the use of an igniting tube and plunger or piston that shall automatically create combustion within the generator or the closed chamber at the moment required for the concatenation of the movements of the engine; fifth, in the combination of the mechanisms necessary to effect the results proposed to introduce the combustible material in the closed chamber into the generator and then to ignite it to produce the combustion required.

To effect the object of my invention, I construct a generator, A, of cast metal, smoothly bored, having flanges on each end to sustain cast heads suitably fastened by bolts. To the bottom or under side of this generator I properly attach a closed chamber, B; and the top of the generator has a flat surface on its outer side to receive a slide valve, E, having openings, P, that in one position of the slide valve correspond and register with openings P' in the flattened portions of the generator, but in the other position of the valve are closed. This valve E is held in place by plates e and e', so screwed to the cylinder that while they leave it free to vibrate, as in a rebate, hold it closely to the ground surface of the generator, and thus it moves with an air-tight joint. The centre of the heads of the generator is provided with stuffing-boxes to receive and support a central shaft, M, to one side of which a wing or plate, Q, is securely fastened that is of dimensions to fit the half internal diameter of the generator but free to vibrate thereon from one side to the other of a diaphragm, O, that is firmly secured longitudinally to the upper interior side of the generator on a line between the opening P' P'; and reaches nearly to or just touching the shaft M at its lower edge, and from one head to the other of the generator the shaft M carries a crank-arm, N, on one end by which it is to be vibrated. A shaft, G', is centrally placed in the close chamber B and supported in a suitable bearing at one end and in a proper stuffing-box at the other end, which passes through the head of the close chamber B and carries a crank-arm, G, to give it vibration. A section, C, of suitable dimension is cut from the bottom of the generator and secured by bolts to the shaft G', and on the opposite side of this shaft is in like manner secured a tube, L, that is wrapped with loose fibrous material. The shaft G' making a half rotation of course removes the section C to the bottom of the closed chamber and the wrapped tube L into the generator; and the lower portion of the chamber B being filled with oil, or some combustible material, the fibrous wrapping will at all times when elevated into the generator be saturated with the fluid. A pipe, H, is inserted in the bottom of the generator, having an outside opening at k, and a piston, I, with a loop, R, at its end, to connect with a suitable mechanism to give it longitudinal intermittent

vibration. The piston I may carry at its inner end a sponge saturated with some very inflammable fluid, or a pellet of gun-cotton, or a fulminate to ignite the saturated tube. When the fluid is relied on a jet of gas or the flame of a lamp at the opening k in the pipe will produce ignition, and as the plunger is pushed forward it will carry the flame to the saturated wrapping on the tube L, but when gun-cotton or a fulminate is relied on to produce the required ignition simple percussion will be sufficient. The piston I terminates in a valve-plug that has its seat in the inner end of the pipe H, so that when the expansion of the air in the cylinder takes place the valve will be closed and prevent any loss of power by the escape of air through the igniting tube. When the connections between the generator, the crank-arms, the valve seat, and piston-rods are properly formed with the working engine, all of which may be done in any of the most approved modes, the operation of my invention will be smooth, regular, and almost without noise. The closed chamber having received its charge of oil, or other combustible material, from any suitable reservoir connected by a pipe and stop-cock, and the parts being in the position shown in fig. 2, with the piston packing saturated with its inflammable liquid and the flame applied to the opening k, the engine is moved a single turn by any means available, when the shaft M will revolve its plate and expel the air behind it through the openings exposed for that purpose by the movement of the valve plate during its passage over them in its movement in the direction required by its connection with the engine. The shaft G' will in its half rotation carry down the section-plate and raise the wrapped tube L charged with oil into the cavity of the generator, the piston will move-forward with its packing ignited by the flame at the opening k and instantly ignite the oil on the fibrous wrapping of the wrapped tube, which will burn rapidly until the oxygen of the air in the generator is consumed, and the utmost pressure capable of being exerted by the heat created will now be attained, when the onward movement of the valve will permit the expanded air to pass into the working cylinder of the engine, and thenceforward keep it steadily in motion, for the repetition of these several steps is all that is required for this purpose, for it is obvious that the return vibration of the plate Q in the generator will expel the burnt air and introduce a body of fresh air necessary to support the required combustion. Should it be found that a single generator would require a length of time to effect its proper combustion inconvenient or not sufficiently economic, it is obvious that two or more may be connected with the same working engine, and then of course this objection would be completely obviated, for the action of each generator would be so timed as to use its expanded air at any instant desired. It is obvious, too, that by rendering the partial vacuum, created by the expulsion of the burnt air from the generator, available at one end of the stroke of the working engine, I can utilize this power instead of letting it go to waste. It is also obvious that other modes of ventilating the generator may be adopted, as, for example, the piston and disk follower, shown in fig. 6, would in its reciprocation evidently effect the result proposed; and it is further obvious that the electric spark may be used under some modifications of my improvement to ignite the combustible matter on the saturated fibrous wrapping on the tube where this is burned, though I do not now claim this.

What I claim as my invention, and desire to secure by Letters Patent, is—

1. A generator for heating the air for an air engine by burning a combustible material contained in a close chamber connected with the generator, substantially as described.
2. A mechanism, substantially such as described, for alternately producing and extinguishing combustion in the generator of an air engine.
3. The combination of the section C of the generator with the tube L and shaft G', substantially as described, to alternately transfer the combustible material from the closed chamber to the generator, as set forth.
4. A mechanism, substantially such as described, for simultaneously expelling the products of combustion from the generator and introducing fresh air therein.
5. The combination of the stationary diaphragm O with the rotating partition plate Q and generator A, substantially as and for the purpose set forth.
6. The igniting tube H, combined with its piston I, substantially as and for the purpose set forth.
7. The combination of the igniting tube with the generator and closed chamber, substantially in the manner and for the purpose described.

In testimony whereof I have hereunto subscribed my name.
